US00D844431S

(12) **United States Design Patent** (10) **Patent No.:** **US D844,431 S**
Carnduff et al. (45) **Date of Patent:** **** Apr. 2, 2019**

(54) **PACKAGE**

- (71) Applicant: **The Gillette Company**, Boston, MA (US)
- (72) Inventors: **Ian Andrew Carnduff**, Brooklyn, NY (US); **Robert Charles Doherty**, Braintree, MA (US); **Graham Clive Hufton**, New York, NY (US); **Richard Kevin Sennett**, Abington, MA (US)
- (73) Assignee: **The Gillette Company LLC**, Boston, MA (US)
- (**) Term: **15 Years**
- (21) Appl. No.: **29/545,878**
- (22) Filed: **Nov. 17, 2015**

Related U.S. Application Data

- (62) Division of application No. 29/496,570, filed on Jul. 15, 2014, now Pat. No. Des. 746,132, which is a division of application No. 29/416,175, filed on Mar. 19, 2012, now Pat. No. Des. 712,248.

Primary Examiner — Brett Miller(74) *Attorney, Agent, or Firm* — Ronald T. Sia; Kevin C. Johnson(57) **CLAIM**

The ornamental design for a package, as shown and described.

DESCRIPTION

FIG. 1 is a perspective view of a package of the present invention;

FIG. 2 is a top view thereof;

FIG. 3 is a bottom view thereof;

FIG. 4 is a right view thereof;

FIG. 5 is a left view thereof;

FIG. 6 is a front view thereof; and,

FIG. 7 is a rear view thereof.

The broken lines depict environmental subject matter only and form no part of the claimed design.

1 Claim, 5 Drawing Sheets(56)
